UNITED STATES PATENT OFFICE

WILLIAM F. CONCANNON, OF BRIDGEPORT, CONNECTICUT.

METHOD OF MAKING SCISSORS, SHEARS, TWEEZERS, AND THE LIKE.

1,407,127.

Specification of Letters Patent. Patented Feb. 21, 1922.

Application filed June 24, 1920. Serial No. 391,261.

To all whom it may concern:

Be it known that I, WILLIAM F. CONCANNON, a citizen of the United States, residing at Bridgeport, county of Fairfield, 5 State of Connecticut, have invented an Improvement in Methods of Making Scissors, Shears, Tweezers, and the like, of which the following is a specification.

This invention relates to the manufacture of scissors, shears, tweezers, and the like and has for its object to provide a simple and inexpensive method whereby articles of the present character may be produced, the novel method of the invention being especially useful in the production of scissors and shears of exceptional cutting and wearing quality by reason of the fact that each of the steps of the method is capable of being practiced upon crucible tool steel of high 20 carbon content.

The members of the scissors, shears, tweezers, and the like, resulting from the novel method of the invention are produced by successive steps performed upon separate 25 strips or pieces of rod or wire, preferably crucible tool steel wire of high carbon content. In practicing the method, I use a strip or piece of rod or wire of any desired length and gauge to form a scissors, shear, or 30 tweezers member of the desired size. The wire is preferably though not necessarily, provided with a groove in one of its ends, is curled to form the bow of the scissors, shear or tweezers member, is offset to give 35 the blade the proper set with respect to the handle, the blade is forged and subsequently trimmed and shaped, the members are tempered and finished, the finishing operation consisting of any desirable and necessary 40 steps, such as grinding the blades, buffing and polishing the blades and handles, electroplating, etc., and the members are finally assembled to produce the finished article.

The method of the invention will now be 45 fully described and will hereinafter be specifically claimed.

In the accompanying drawing forming a part of this specification,

Fig. 1 is a view of a strip or piece of wire 50 from which the scissors, shear or tweezers member is to be formed;

Fig. 2 is a view of the wire after it has been curled to form the bow;

Fig. 3 is a view showing the bowed wire 55 after it has been offset;

Fig. 4 is a view showing the bowed and

offset wire after the forging operation of the method has been performed;

Fig. 5 is a view of a scissors or shear member complete; 60

Fig. 6 is a view of a pair of scissors or shears composed of two members similar to the member of Fig. 5; and

Fig. 7 is a view of a pair of tweezers made in accordance with the principles of 65 the invention.

10 denotes a strip or piece of wire, preferably crucible tool steel wire, of any desired length and gauge, depending upon the shape and size of the scissors, shear, or tweezers 70 member to be formed. The strip or piece of wire is preferably, though not necessarily, provided with a groove 11 in one of its ends. The wire as shown in Fig. 1 of the drawing may be first curled to form the bow 12, as 75 in Fig. 2, and then offset, or may be offset as afterwards formed. The curling and offsetting may be singly or jointly performed either by hand or in any other suitable manner, as by placing the wire in a fixture made for the purpose. As disclosed very clearly in the drawing, the groove in the end of the wire is adapted to allow the end of the wire to fit closely to the handle of the member 85 after the bow is formed. It will be obvious that the provision of the groove in an end of the wire forms no essential step in the manufacture of the members. It will likewise be obvious that the bow can be made 90 to assume any desired shape or style and can be made any desired size; and that the offsetting can be done at any desired location on the strip or piece of wire and can be as pronounced as may be desirable to form a 95 blade suitable for scissors, shears, tweezers, or the like. Should it be found desirable, the offsetting step of the method can be dispensed with.

After the bow has been formed, and after 100 the handle has been properly offset to give the portion of the wire, denoted by 14, that is to form the blade the proper set with respect to the handle, the member is ready for the forging operation of the method, which, 105 as suggested in Fig. 4, is performed upon the portion of the wire that is to compose the blade. It is an easy matter to obtain a blade of any desired shape, such for example as an oval blade, a double swaged blade, a 110 square or flat blade, a blade suitable for tweezers, or the like, by means of dies made

and sunk for the purpose. It will be evident that the blade may be forged to provide a shoulder 15 as is usually found in scissors, or the blade may be forged without this shoulder.

5 After the blade has been forged it is next trimmed to shape, as suggested in Figs. 4 and 5. The trimming can be done in any desired or preferred manner.

10 The member is now ready for the tempering, finishing and assembling operations, which may be performed in any ordinary or preferred manner and in any suitable sequence. I preferably proceed in the following manner. After the handle has been curled to form the bow and the blade has been offset, forged and trimmed to shape, I match the blades with each other and then drill them, as suggested at 16 in Fig. 5, to 20 make them ready to be assembled by means of a screw or a rivet as may be desirable. I next temper each member in a well known manner by applying to it the proper degree of heat for the necessary period of time to 25 give to the material used the desirable cutting and wearing qualities. I next grind the blade in a manner also well known, and preferably use for this purpose a stone or emery wheel upon which water is allowed to run 30 to keep the member cool for an obvious reason. The handle and bow is finished and polished on a buff wheel made of muslin or cotton with emery and grease applied, and the blade is polished on a wood wheel dressed 35 with emery, grease and wax, to prepare the member for electroplating which is done in usual manner. After the electroplating has been accomplished, the member is buffed on a cotton buff made of muslin and run at high 40 speed, a composition of lime and wax being applied to the cotton buff to give the metal, usually nickle, a brilliant luster. The blade is finally sharpened, in the case of scissors, shears, and the like, to give it the proper 45 cutting edge. This is a delicate operation and must be performed by an expert.

The members are next assembled, and after being assembled the blades are prop-

erly set for cutting. A final buffing is given to insure the brilliant luster of the metal, 50 and after cleaning the finished article with a soft cloth it is ready for the market.

It is essential, when manufacturing scissors of the present type, that the blades be located at predetermined distances from the 55 handles in order that the members can be properly united, and the finished scissors can be evenly balanced. The position of the offset can vary to a slight extent, an amount greater than the variations in shapes and 60 sizes of the formed bows. I have found in practice that it is preferable to measure from the free ends of the formed bows, after the same have been set to locate the positions of the blades, this for the reason that there are 65 variations in shapes and sizes of the curled bows. Furthermore, in the manufacture of scissors from high carbon steel, no difficulty is experienced in performing the offsetting and bowing operations while the metal is 70 cold. The heat required to forge the blades necessarily disturbs the nature of the steel of the handle so that the handle chills and can not then be turned cold without breaking.

75 What I claim is:

1. The method of making the members of scissors, shears, tweezers and the like, which consists in first curling a strip or piece of wire to form the bow of the member, offsetting the strip or piece to make provision for the blade of the member, and in finally locating the blade and forging and trimming the same to proper shape and size.

2. The method of making the members of 85 scissors, shears, tweezers and the like of tool steel of high carbon content, which consists in curling and offsetting a strip or piece of wire while cold to form the bow of the member and to make provision for locating the 90 blade of the member, and in afterwards locating the blade and forging and trimming the same to proper shape and size.

In testimony whereof I affix my signature.

WILLIAM F. CONCANNON.
